UNITED STATES PATENT OFFICE.

EDWARD W. DORSEY, OF NEWARK, OHIO.

RAIL-LOCK.

1,312,621.

Specification of Letters Patent. Patented Aug. 12, 1919.

Application filed May 5, 1919. Serial No. 294,832.

To all whom it may concern:

Be it known that EDWARD W. DORSEY, a citizen of the United States of America, residing at Newark, in the county of Licking 5 and State of Ohio, has invented certain new and useful Improvements in Rail-Locks, of which the following is a specification.

The present invention relates to improvements in rail locks, designed for use on 10 railways to couple the adjoining rails, particularly the converging rails of a switch or cross-over with the track rail of the main line of a railway track. As is well known the passing of the rolling stock over the 15 tracks, especially when the traffic is in one direction only, causes the rails to creep, and this creeping of the rails, especially at the junction of a switch with the main-line, frequently causes the replacement of switch 20 rails to correct the alinement of the tracks, and requires continuous attention for readjusting the rails.

The purpose of my invention is to provide means for locking the adjoining rails 25 of the switch and main track so that they will creep or move in unison, and movement of one rail, independent of the adjoining rail, is prevented. Thus when a train is 30 passing over the main track, the rails ahead of it are depressed and are caused to creep with the approach of the heavy load, and the presence of the rail lock of my invention causes the switch rail that is coupled with the main track rail to move in unison 35 with the main track rail and maintain its same relative position with regard to the main track. If the railway be a one track line, *i. e.*, with trains passing in both directions on the same track, the adjoining rails 40 and their coupling members forming the lock, are maintained in normal relationship one with another and disarrangement of the switch or track rails is prevented.

As the load of the approaching train 45 comes on the tracks or rails, the latter are depressed, and to compensate for this action, and prevent dislocation or disarrangement of the lock members, I provide for a relative vertical movement of the members of 50 the locking device, but cause the parts to be so locked as to prevent independent movement of the rails in the direction of travel of the passing rolling stock.

The invention consists in certain novel 55 combinations and arrangements of parts as

hereinafter described and claimed, and in the accompanying drawings I have illustrated one complete example, and a slightly modified form, of the physical embodiment of my invention, according to the best mode 60 I have so far devised for the practical application of the principles of my invention.

Figure 1 is a plan view of a railway track showing the junction therewith of a switch or cross-over, and between a pair of adjoining and converging rails the rail lock 65 of my present invention is utilized.

Fig. 2 is a plan view, enlarged, of the lock device.

Fig. 3 is a vertical, transverse sectional 70 view on line 1—1 of Fig. 2.

Fig. 4 is a plan view showing the lock members arranged in different relative positions from that of Fig. 1.

Fig. 5 is a modified form of the invention, 75 wherein are employed different attaching flanges or plates for the lock members.

Fig. 6 is a sectional view illustrating the possible vertical movement of one lock member and rail with relation to the complementary member and rail, as one rail is depressed from a passing load. 80

In Fig. 1 a plan view of a portion of a railway is illustrated, showing the main track rails 1, 1, and the switch or cross over 85 rails 2, 2, provided with the usual frog 3, and the rails 4 of the switch and 4' of the track, as they converge, are provided with the device of the invention as indicated at D in Fig. 1, and the usual switch lever mechanism is indicated at 5 also in said figure.

The rail lock is made up essentially of the two members 6 and 7, the former a head with rounded sides and flat top and bottom faces, and the latter a circular socket member adapted to receive the head and conforming to its configuration, and open at the top and bottom. These respective members are fashioned with flanges or plates 8 and 9 for attachment to the web of the rails 100 by the usual bolts 10 in connection with the lock plates 11, and secured by nuts 12 on the bolts, washers 13, and finally the cotter pins 14 as passed through the bolts to prevent dislocation of the nuts. 105

In Fig. 5 a somewhat modified form of the device is indicated, the head being designated 6' and the socket 7', while the flanges or plates 8' and 9' extend equidistant at both sides of the member that they carry. 110

As shown the lock members are so coupled together that the approaching train on the main track 1, 1, in Fig. 1, will depress and push ahead of it the track or rail designated 4' and the rail may be depressed independent of the rail 4 because of the open top and bottom socket member which permits the head 6 to have vertical movement relatively to it, as indicated in Fig. 6. The creeping movement of the rail 4' however is imparted to the rail 4 through the lock joint D and these two rail members are thus kept in constant relationship one with the other.

The lock is thus flexible in its connection with the rails and its members are independently movable with relation to each other, and the vertical movement between the parts or members eliminates the likelihood of breakage of parts. In Fig. 4 the parts are shown as arranged between converging rails wherein spike plates, bolts, etc., may be present in the tracks making it necessary to align the flanges rather than locate them abreast of each other. The plates of the lock members are made to conform to the outline of the web of the rails, and thus the members may be rigidly and securely bolted to the rails without likelihood of displacement.

The bolting flanges 8 and 9 may be made

to conform with, and in some cases, replace the usual angle, fish, or splice plates.

In the modified form of Fig. 5 the socket member extends about the head, holding the members together and preventing spreading of the rails.

What I claim is—

1. The combination with the pair of rails and an attaching plate bolted to each, of a socket member on one plate and a head member on the complementary plate fitted together and adapted for relative vertical movement.

2. The combination with the converging rails, of a lock device coupling said rails and comprising a socket member and a head member therein and said members adapted for relative vertical movement.

3. The combination with the adjoining rails angularly disposed, of a flexible locking device comprising a socket member forming a partly closed annular recess open at top and bottom, and a head member fitted in said recess as described, and attaching plates for each member secured to the respective rails.

In testimony whereof he affixes his signature.

EDWARD W. DORSEY.
